UNITED STATES PATENT OFFICE.

JOHN W. DOLLMAN, OF PARKERSBURG, WEST VIRGINIA.

FASTENING DEVICE FOR SHIPPING-TAGS.

No. 829,062.

Specification of Letters Patent.

Patented Aug. 21, 1906.

Application filed March 9, 1906. Serial No. 305,049.

To all whom it may concern:

Be it known that I, JOHN W. DOLLMAN, a citizen of the United States, residing at Parkersburg, in the county of Wood and State of West Virginia, have invented certain new and useful Improvements in Fastening Devices for Shipping-Tags; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to fastening devices for shipping-tags, and is especially designed for tagging such articles as goods which come in bales, meat, &c.

The object of the invention is to provide a securing device which enters the goods to which the tags are attached in such a manner as to render their attachment most secure.

Preceding a detail description of the invention, reference is made to the accompanying drawings, of which—

Figure I shows my fastening device united to a tag and ready for attachment to the article to which the tag is to be applied, a part of the tag in this view being broken away. Fig. II is a view of the opposite side of the tag as shown in Fig. I. Fig. III is a side edge view of Fig. I. Fig. IV is an edge view looking in the direction of the fastening device as shown in Fig. I.

In a detail description of the invention similar reference characters indicate corresponding parts.

The fastening device 1 is essentially constructed of sheet metal having its longitudinal edges reinforced by turning said edges over, as shown at 2 2, said reinforced edges extending throughout the sides of the fastening device to the end of the tag 6. The entering end 3 of said fastening device is pointed or spear-shaped, having rearwardly-extended spurs 4 4, which engage the article when the device is inserted therein and offer resistance to the withdrawal of the device. In addition to these resisting-spurs 4 4 there are two inwardly-lying spurs 5 5, which project inwardly upon the top side of the device

and offer additional resistance to the withdrawal of the device from the goods. These additional spurs 5 5 are stamped from the same piece of metal and are turned inwardly, substantially as is shown in the drawings, and the said spurs 5 5 and 4 4 offer a continuous line of resistance across the head 3 of the device at the point where said head joins the main body of said device. The reinforced edges 2 2 impart to the attachment a desirable strength that insures the head of the device penetrating the goods without the danger of the fastener buckling at the body. The said reinforced edges are formed by turning the metal over in stamping the same. The fastener is secured to the tag 6 by means of an opening 8, through which is passed a series of ears 7, also stamped from the end of the fastener and bent over to clamp one side of the tag. Of course the fastener may be united to the tag in a variety of ways, but the manner of uniting the same to the tag as above indicated is a convenient and efficient way.

Having described my invention, I claim—

1. A fastening device for the attachment of shipping-tags to goods, consisting of a body portion 1 having a spear-shaped head 3 with rearwardly-extended spurs 4 4 and inwardly-extending spurs 5 5 in the rear of the head and having points substantially in the same plane with the points of the spurs 4 4, substantially as specified.

2. In a fastening device for attaching shipping-tags to articles, a body portion 1 having its longitudinal edges reinforced to strengthen the body portion, the free end of said device being pointed and having outwardly and rearwardly extending spurs 4 4, and additional spurs 5 5 turned inwardly over the body of the device and having points substantially in the same plane with the points of the spurs 4 4, thus forming a transverse line of resisting-spurs at the entering-point of the device, substantially as specified.

In testimony whereof I affix my signature in presence of two witnesses.

JOHN W. DOLLMAN.
